(57) CLAIM

The ornamental design for a football marquee light, as shown and described.

DESCRIPTION

FIG. 1 is a perspective view of our football marquee light; FIG. 2 is a front view thereof; FIG. 3 is a back view thereof; FIG. 4 is a left side view thereof; FIG. 5 is a right side view thereof; FIG. 6 is a top view thereof; and, FIG. 7 is a bottom view thereof.

The broken lines shown on the drawings depict portions of the football marquee light that form no part of the claimed design.
